UNITED STATES PATENT OFFICE.

FRANCIS B. LOVE AND BOYD H. SMITH, OF SHELBY, OHIO, ASSIGNEES TO THE AUTOCALL COMPANY, OF SHELBY, OHIO, A CORPORATION OF OHIO.

CASE FOR FIRE-ALARM SIGNALING MECHANISM AND THE LIKE.

Application filed February 17, 1925. Serial No. 9,830.

This invention, as indicated, relates to a casing and a closure co-operating therewith and adapted particularly to receive the signaling mechanism of a fire alarm system.

5 In an apparatus of the character referred to it is desirable to have ready access to the signal sending mechanism without detaching the same completely from the casing. In many types of fire alarm boxes the closure 10 is completely removed and the mechanism is swung in suspended position from the lead wires. This practice not infrequently results in the placing of too great a strain upon said wires and causing disconnection of the 15 conductors from their associated parts and rendering the device unsuitable for the use intended.

The principal object of the present invention is to obviate the disadvantages referred 20 to and to provide a casing and closure which will co-operate to support the signaling mechanism in a position where ready access to the same may be had for purposes of inspection and repair. Another object of the 25 invention is to provide a casing and closure which will securely house the mechanism protected thereby and which may be readily installed in structures of different character, being particularly adapted to be set into the 30 wall of a building. A further object of the invention is to provide a construction which will facilitate the installation of the electrical signaling apparatus after the casing has been set into the wall of a building and 35 the interior trim has been put in place. Other objects of the invention will appear in the course of the following description. To the accomplishment of the foregoing and 40 related ends, said invention, then, consists 45 of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:—

50 Fig. 1 is a front elevation of a fire alarm box embodying the principles of the invention; Fig. 2 is a top plan view of the apparatus shown in Fig. 1, with the closure seated upon the casing; and Fig. 3 is a top plan view of the apparatus shown in Fig. 55 1, with the closure and the housing for the

fire alarm mechanism shown in full lines in a position in which ready inspection of the mechanism may be made, and showing in dotted lines a second position in which said closure and housing may be placed for purposes of inspection or repair to lead wires, etc.

As is more particularly shown in Fig. 3 of the drawing, the apparatus comprises a casing 1 of oval outline as viewed from the front and provided on its upper side with an extension 2 apertured to receive a conduit 3 within which the lead-in wires (not shown) for the electrical signaling apparatus are enclosed. At one side of said casing a pair 60 of bosses 4, 5, are provided on the upper and lower inner walls of said casing adjacent the forward edge thereof, said bosses having integral studs 6, 7, projecting inwardly therefrom. Said studs are provided with horizontal apertures 8 within which cotter pins 9 may be inserted.

Said casing is closed at its base and is open at its forward side and a closure 11, preferably of oval outline of substantially the same diameter as that of the casing, is adapted to be secured to the open side of said casing by suitable locking means (not shown). Apart from said locking means said closure is adapted to be connected with said casing by means of a pair of supporting or bracket arms 12, preferably formed of steel straps, apertured at their respective ends, to enable the same to be pivotally connected with said casing and said closure. 70 The apertures at one end of said arms are adapted to be fitted over the respective studs 6 and 7, above referred to, and the arms are maintained in pivotal relation with said studs by means of the cotter pins 9. The 75 opposite ends of said arms 12 are adapted to be secured, by means of pivot pins 13 passing through said apertures, to a pair of ears 14 provided upon the inner wall of said closure 11 upon the side opposite the position 80 of the studs 6, 7, carried by said casing.

The closure plate is preferably provided with a circumferential flange extending inwardly and may terminate in a beaded edge 15 at the point where it fits against the outer edge of said casing. On the inner side of said closure plate, in spaced relation to the circumferential flange thereof, an upstanding flange 16 of oval outline is provided. Said flange is provided with a plurality of 105 110

offset lugs 17 having screw-threaded apertures. A housing 18, of substantially oval form corresponding with the outline of the upstanding flange 16 heretofore referred to, is provided to enclose the mechanism of the signaling system forming a dust cover therefor, and is adapted to be secured to the upstanding flange 16 heretofore referred to by means of a plurality of screws 19 engaged through a plurality of ears 21 formed on the margin of said housing 18 in alignment with the offset lugs 17 of said closure plate. Said housing may be formed with a flat top face 22 to permit the same to pass more readily within the space between the pair of supporting arms 12 carrying the closure plate.

The signaling mechanism may be attached to the inner face of the closure plate or to the housing secured thereto in any preferred manner and the details of such signal mechanism form no part of the present invention.

The supporting arms 12, it will be noted, provide a wide range of motion for the closure plate which may be swung about the pair of pivots 13 as well as with said arms 12 about the pivots provided by the studs 6 and 7. In this manner the housing 18 may be almost completely reversed from its position within the casing and upon its removal from the closure plate ready access may be had to the electrical signaling mechanism.

Through the spacing of the supporting arms 12 upon opposite sides of the housing 18, the apparatus is adapted to be completely self-contained. There are no external hinges to invite tampering with said apparatus by unauthorized persons and when the closure is locked against the open side of the casing by means of suitable lock screws (not shown), the apparatus is substantially protected against injury from without.

While the invention has been described in connection with a fire alarm signal box, it is obvious that the closure herein provided is adapted for uses other than those herein particularly described. The same type of hinge may be used without change for a box wherein the closure is of the semi-flush as well as of the surface type. The parts may thus be standarized and the same hinge parts on the casing may be used to support a closure of either type of construction. The con-

struction also lends itself to rapid installation after the casing has been built into the wall of the building and the interior trim has been put in place. The fire alarm mechanism is secured within the housing to the inner wall of the closure and said assembled mechanism may be then attached to the casing by hooking the free ends of the supporting arms over the studs on said casing and placing the cotter pins through the apertures provided therein. The lead wires can then be connected to the terminals of the fire alarm mechanism and the closure seated upon the outer face of the casing and held thereagainst by means of suitable lock screws.

Other modes of applying the principle of our invention may be employed instead of the one explained, change being made as regards the mechanism herein disclosed, provided the means stated by the following claim or the equivalent of such stated means be employed.

We therefore particularly point out and distinctly claim as our invention:

In an article of the character described, the combination of a casing having a base and an outwardly extending flange, a closure adapted to fit snugly against the edge of said flange throughout its entire extent, a flange projecting inwardly from the inner face of said closure and spaced from said casing flange when said parts are engaged, a housing engaged upon the inner edge of said closure flange, a pair of parallel bracket arms positioned respectively on opposite sides of said housing and in spaced relation thereto, a pair of bosses, within the casing flange and spaced from the edge thereof, having pivoted pins to engage with apertures formed in the inner ends of said bracket arms, removable locking pins engaged through said pivot pins to detachably hold said bracket arms thereon and a pair of apertured ears on the inner wall of said closure on the side opposite the position of the bosses on said casing to receive pivot pins extending through apertures in the opposite ends of said bracket arms, whereby a wide range of motion may be provided for said housing and closure.

Signed by us this 14 day of Feb., 1925.

FRANCIS B. LOVE.
BOYD H. SMITH.
